MICROTOME BLADE GUARD

Louis A. Robertson, Edgewood, Md., assignor to the
United States of America as represented by the Secretary
of the Army

Filed Aug. 1, 1963, Ser. No. 76,069

Term of patent 14 years

(Cl. D16—2)

(Granted under Title 35, U.S. Code (1952), sec. 266)

Fig. 1

Fig. 2

Fig. 3

Fig. 4

FIG. 1 is an end view of the microtome blade guard;
FIG. 2 is a side view of the same;

FIG. 3 shows the guard in perspective, and

FIG. 4 is a perspective view of the microtome blade guard mounted on the microtome. The broken lines are shown for illustrative purposes only.

The invention described herein may be manufactured and used by or for the Government for governmental purposes without the payment of royalty thereon.

I claim:

The ornamental design for a microtome blade guard, as shown and described.
